Inventor:

J. R. Cameron

UNITED STATES PATENT OFFICE.

J. R. CAMERON, OF PITTSBURG, PENNSYLVANIA.

IMPROVEMENT IN TRACTION-WHEELS.

Specification forming part of Letters Patent No. 38,164, dated May 12, 1863.

To all whom it may concern:

Be it known that I, J. R. CAMERON, of Pittsburgh, in the county of Allegheny and State of Pennsylvania, have invented a new and useful Improvement in Traction-Wheels; and I do hereby declare that the following is a full, clear, and exact description thereof, reference being had to the accompanying drawings, which form part of this specification, and to the letters of reference marked thereon.

My invention relates to an improvement in that class of traction-wheels wherein a series of movable plates are placed upon the periphery of a wheel for the purpose of causing it to hold firmly to the ground, and to prevent slippage while drawing heavy loads.

My improvement consists in securing a number of "feet" to the wheel by a bolt passing through the center of each, so as to enable them to vibrate or rock from heel to toe upon the surface of the wheel in such a manner as to present the entire face or tread of each foot alternately to the ground, before the one immediately preceding it is lifted up. Upon each of these feet I have formed a "heel and toe" by turning the rear and forward end upward and outward, which, as they come round in turn, press into the ground, whereby I am enabled to draw a heavy load over rough and irregular roads with less slippage and greater ease than by any other plan yet devised for the same purpose.

To enable others skilled in the art to fully understand my improvements, I will proceed to describe its construction and operation by reference to the accompanying drawings, in which—

Figure 1 represents a perspective view of my improved traction-wheel. Fig. 2 represents a transverse vertical section of the same.

All the drawings are lettered, and similar letters indicate like parts on all the figures.

I construct my wheel in any of the known ways, but prefer to make it double—that is, with two hubs, T T, of corresponding size upon the same shaft H, with spokes P radiating from each and terminating in separate and distinct rims B B of equal diameter. I do this for the purpose of securing a light wheel with a broad surface or tread, and to avoid clumsiness in appearance. Around the outside of the rims B B is a deep channel or groove, in which the

feet N N are secured and vibrate. These feet I make of boiler-iron of the requisite thickness to withstand the pressure of the wheel without bending, and are formed by bending square plates of iron (rather larger than the breadth of the wheel) down at the sides the depth of the channel in the rims B B, and rounding the parts so bent down as to enable them to rock on the bolts s s s, by which they are held in the grooves or channels aforesaid. The edges of these plates transverse to the line of tread are turned upward and outward so as to project above the plates two inches or more at the option of the constructor, for the purposes hereinbefore stated.

The operation of my wheel is as follows: The wheel being secured in a proper frame to the object it is intended to draw, and motion being transmitted through the medium of the shaft H, the wheel as it revolves carries with it the feet N N N on its periphery, which, as they in turn come in contact with the ground, present one of the projections L L, Fig. 1, when the foot, vibrating upon its pivot S, allows both ends to strike the ground almost simultaneously, thus keeping the broad surface of one or the other of the feet continually in contact with the earth. As the wheel progresses the full tread of each foot is alternately bearing on the ground before the one immediately preceding it is lifted up, as previously stated, whereby I am enabled to draw greater loads upon rougher roads with a lighter wheel than any other in present use.

Having thus described my improvement in traction-wheels, what I claim is—

1. The use of vibrating feet N N N upon the periphery of a wheel, when constructed in the manner and for the purposes as herein set forth.

2. Turning up the edges of the plates so as to form a heel and toe, substantially in the manner as hereinbefore stated.

3. The use of a double wheel, in combination with the vibrating feet turned up at their edges in the manner and for the purposes as herein previously stated.

J. R. CAMERON.
